UNITED STATES PATENT OFFICE.

LAURENCE A. HAWKINS, OF SCHENECTADY, NEW YORK, ASSIGNOR TO GENERAL ELECTRIC COMPANY, A CORPORATION OF NEW YORK.

RELAY FOR BLOCK-SIGNAL SYSTEMS.

967,192.

Specification of Letters Patent. Patented Aug. 16, 1910.

Application filed February 19, 1906, Serial No. 301,725. Renewed March 4, 1908. Serial No. 419,197.

To all whom it may concern:

Be it known that I, LAURENCE A. HAWKINS, a citizen of the United States, residing at Schenectady, in the county of Schenectady, State of New York, have invented 5 certain new and useful Improvements in Relays for Block-Signal Systems, of which the following is a specification.

My invention relates to track relays for 10 block signal systems, and its object is to provide a novel, efficient and reliable form of three-position relay.

My invention is particularly applicable 15 for use in systems of the type disclosed in my former application, Serial No. 217,212, filed July 19, 1904, in which track relays having operative positions on both sides of the off-position are employed for controlling signals giving three different indications.

20 The purpose of my present invention is to arrange a relay of this character so that it will have a positive off-position; thereby preventing the possibility of its swinging from one operative position to the other 25 when the relay is deenergized.

More specifically stated, my invention consists in a relay comprising a movable contact member having operative positions on both sides of its off-position, means operative 30 upon the deenergizing of the relay for locking the member in off-position, and means for releasing the member automatically when the relay is energized.

My invention will best be understood by 35 reference to the accompanying drawings, in which—

Figure 1 shows diagrammatically a block signal system comprising track relays arranged in accordance with my invention; 40 Fig. 2 shows an end elevation of the relay; Fig. 3 shows a plan view of the same; and Fig. 4 shows a side elevation.

In Fig. 1, R, R' and R² represent the 45 rails of portions of three blocks of a block signal system. The home signal H and distant signal D are stationed at the entrance to the block R, and the signals H' and D' at the entrance to the block R'. By employing home and distant two-position signals three distinct indications,—viz., danger, caution and clear may be given, but my invention is not limited to the use of separate home and distant signal-arms, but is equally applicable to the control of one-arm, three-position, signals.

b' and b² represent track batteries supplying the blocks R' and R², respectively. In my former application I showed a block signal system employing alternating-current, but since the kind of current employed 60 is entirely immaterial as regards my present invention, I have indicated track batteries for the sake of simplicity. The track battery b' is connected to the track circuit through a reversing switch S controlled by 65 the operating mechanism h of the home signal H. This operating mechanism is merely indicated diagrammatically, since it forms no part of my invention and may be of any well-known type. 70

The operating mechanism for the distant signal D is indicated at d.

B represents the source of current for the operating mechanism h and d.

The track relays are of the type shown 75 in my earlier application, comprising two coöperating coils,—one, A, connected to the track, and the other, a, which is shown as movable, supplied with current independently of the track circuit. 80

C represents a contact member carried by the movable coil a. With this type of relay, if either coil is deenergized, the relay possesses no torque, and when current is flowing through both coils, the direction of 85 torque depends upon the relative directions of current-flow in the two coils. Consequently, by supplying the two coils from separate circuits and reversing the current-flow in one circuit, the relay may be caused 90 to assume a position on either side of off-position.

E represents a locking device which automatically locks the contact member in off-position when the relay is deenergized, and which automatically releases it when the relay is energized. The construction and arrangement of this locking device will be described hereafter.

The operation of the system, as above described, is as follows: With a train in the block R, as indicated in Fig. 1, the relay coil A connected to the track circuit is short-circuited so that the relay has no torque and stands in off-position, to which it has been 105 returned by gravity, and in which position it is locked by the locking member E. With the contact member C in off-position, the circuits of both operating mechanisms h and d are broken so that signals H and D are both 110

allowed to go to danger by gravity, thereby giving the danger indication. With the home signal H in danger position, the reversing switch S is in such a position that 5 the direction of current-flow in the relay coil A' bears the proper relation to the direction of flow through the coil a' to cause the contact member C' to move toward the right, as shown in the figure. Since the 10 relay is energized, the locking member E' is moved out of locking position. In this position of contact member C' the circuit of the operating mechanism h' is energized so that the home signal H' is moved to clear- 15 position, while the operating mechanism d' is deenergized so that the distant signal D' is at danger, thereby indicating "caution." When the train moves out of the block R the 20 relay coil A will be energized and the contact member C will move to the right, thereby putting home signal H at clear. This movement of the home signal reverses the direction of current-flow in the track circuit of R' , thereby reversing the torque in the 25 track relay connected to that block. Contact member C' will, consequently, move to the left, closing the circuit of both operating mechanisms h' and d' , so that both signals H' and D' will be moved to clear, thereby 30 giving "clear" indication. If the locking devices were not employed on the track relays, it is evident that the off-position of the track relays would not be so positive 35 as in the case of a two-position relay where the contact member rests against a stop in off-position. Consequently, under some circumstances, especially where spring contacts are employed, the contact member might move from one operative position over to 40 the other when the relay is deenergized, so as momentarily to close the circuits controlled in that other position.

My present invention consists in providing suitable locking means for giving the 45 relay a positive off-position, and at the same time leaving it free to move to either operative position when the relay is energized. The construction of the relay is shown in Figs. 2, 3 and 4. In these figures the coils 50 A are shown mounted on a rectangular core, between the poles of which the movable coil a is carried on a pivot a' , which also carries the contact member C adapted to engage the stationary contacts c on either side of the 55 mid-position. For direct-current work the coil a may be omitted and a permanent magnet employed for the movable armature. For alternating-current work the relay should be laminated, as indicated.

60 E represents the locking member, which is carried on a pivot e . When the relay is de-energized, this locking member assumes the position shown in Figs. 2 and 4, in which position it is adapted to engage the tongue f 65 projecting from the lower side of the mov-

able core. The engaging portion of the member E is forked, the prongs of the fork being just outside of the path of movement of the tip of the tongue f , as indicated by the dotted line in Fig. 2. Just inside of the 70 prongs are light leaf springs e' , which project across the path of movement of the tip of the tongue f . The purpose of this arrangement is to enable the relay armature to return to off-position from either operative 75 position, but to prevent its movement from off position, as long as the locking member is in the position shown. When the tongue f is moving from either operative position to mid-position, it engages the end of one of 80 the light leaf springs e' . This spring, since it is not supported on its inner side, bends 85 easily, allowing the tongue f to pass. As the motion of the tongue continues until it strikes the inner side of the other leaf spring, 90 it will be stopped thereby, since the other spring is supported on its outer side by the rigid prong of the member E . The small portion of the leaf spring that projects beyond the prong is not long enough to bend 95 sufficiently to allow the tongue f to pass. Consequently, this construction allows the relay to move freely from either operative position to off-position, regardless of the position of the locking member E , but prevents the movement of the relay from off-position as long as the locking member is in locking 100 position.

The locking member E carries the armature G of magnetic material, which acts both 100 as a weight to hold the member E in locking position as long as the relay is deenergized, and also as a means of moving the locking member from locking position when the relay is energized. This armature G 105 extends into a gap in the magnetic core of the track coils A , so that when the track coils of the relay are energized the armature G is drawn upward against a stop g , thereby moving the locking member out of engagement with the movable armature. 110

While I have shown the locking member controlled by the flux of the relay itself, this is not essential to my invention. Any other suitable arrangement may be employed 115 for shifting the locking member when the relay is energized and deenergized. The construction of the relay may be altered, as desired, and the connections and relative positions of the coils may be varied. Accordingly, I do not desire to limit myself to the particular construction and arrangement of parts here shown, but aim in the appended claims to cover all modifications which are within the scope of my invention. 120

What I claim as new and desire to secure by Letters Patent of the United States, is:

1. In a relay, a movable contact member having operative positions on both sides of its off-position, means operative upon the de- 130

energizing of said relay for locking said member in off-position, and means for unlocking said member automatically when said relay is energized.

5 2. In a relay, a movable contact member having operative positions on both sides of its off-position, means for locking said member in off-position, and means for rendering the locking means inoperative when the relay is energized.

10 3. In a relay, a movable contact member having operative positions on both sides of its off-position, means for locking said member in off-position, and means controlled by the current in the relay for rendering the locking means inoperative when the relay is energized.

15 4. In a relay, a movable contact member having operative positions on both sides of its off-position and adapted to return by gravity to off-position when the relay is de-energized, and means for stopping said member in off-position when returned thereto by gravity.

20 5. In a relay, a movable contact member having operative positions on both sides of its off-position, means for engaging said member to hold it in off-position, and means for moving said holding means out of engagement with said member when the relay is energized.

25 6. In a relay, a movable contact member having operative positions on both sides of its off-position and adapted to return by gravity to off-position when the relay is de-energized, and a locking member controlled by the current in the relay and movable by gravity to engage and lock said contact member in off-position.

30 7. In a relay, a movable contact member having operative positions on both sides of its off-position and adapted to return by gravity to off-position when the relay is de-energized, a movable locking member adapt-

40 ed to engage and lock said contact member in off-position, and an armature operatively connected to said locking member and adapt-

ed to be attracted by the flux in said relay to move said locking member from locking position.

50

8. In a relay, a movable contact member having operative positions on both sides of its off-position, two electrically independent windings coöperating to move said member, means operative upon the deenergizing of one of said windings for locking said contact member in off-position, and means for unlocking said member automatically when said winding is energized.

15 9. In a relay, a movable contact member having operative positions on both sides of its off-position, two electrically independent windings coöperating to move said member, one of said windings being carried on the movable member, means operative upon the deenergizing of one of said windings for locking said contact member in off-position, and means for unlocking said member automatically when the last mentioned winding is energized.

70

10 10. In a relay, a movable contact member having operative positions on both sides of its off-position, means for locking said member in off-position arranged to permit the return of said member from either operative position to off-position but to prevent its movement from off-position, and means for rendering said locking means inoperative when the relay is energized.

75

11. In a relay, a movable contact member having operative positions on both sides of its off-position, means for locking said member in off-position arranged to permit the return of said member from either operative position to off-position but to prevent its movement from off-position, and electromagnetic controlling means for said locking means.

80

In witness whereof, I have hereunto set my hand this 16th day of February, 1906. 90

LAURENCE A. HAWKINS.
